UNITED STATES PATENT OFFICE.

TURVETT B. HARLAN, OF ALBA, PENNSYLVANIA.

RATCHET-WRENCH.

1,115,532.

Specification of Letters Patent.

Patented Nov. 3, 1914.

Application filed April 27, 1914. Serial No. 834,836.

To all whom it may concern:

Be it known that I, TURVETT B. HARLAN, a citizen of the United States, residing at Alba, in the county of Bradford and State 5 of Pennsylvania, have invented certain new and useful Improvements in Ratchet-Wrenches, of which the following is a specification, reference being had to the accompanying drawings.

10 This invention relates to new and useful improvements in wrenches, and more particularly to that class generally known as ratchet wrenches.

An object of this invention is the provision of a ratchet wrench consisting of a 15 pair of pivotally connected jaws, the jaws being adapted to support a rotatable head therebetween, the periphery of the head being formed with a plurality of ratchet teeth, 20 and the jaws carrying spring pressed pawls or dogs on opposite sides of the head for engagement with the teeth, to prevent relative movement of the head in one direction with relation to the jaws.

25 A further object of this invention is the provision of a wrench of this character in which the jaws are adjustably connected to receive rotatable heads of various sizes for use in connection with various sizes of work 30 to be turned by the wrench.

A still further object of this invention is the provision of a ratchet wrench in which a plurality of interchangeable rotatable heads are provided, whereby the wrench is 35 adapted for various uses, and for engagement with different kinds and sizes of objects.

With these and other objects in view, my invention consists in the novel construction, 40 combination, and arrangement of parts to be hereinafter more fully described, claimed, and illustrated in the accompanying drawings, in which,

Figure 1 is a side elevation partly in section of my improved wrench, showing the same before the jaws have been tightly closed against the periphery of the rotatable head; Fig. 2 is a sectional view on the line 2—2 of Fig. 1; Fig. 3 is an inner edge view 50 of one of the members of the wrench; Fig. 4 is an elevation showing an alternative form of rotatable head; and Fig. 5 is an elevation showing still another alternative form of head.

Referring more particularly to the drawings, the numerals 1 and 2 designate a pair of pivotally connected members which are curved at one end to form handles 3, and are formed at their opposite end with substantially semi-circular jaws 4. A bolt 5 is 60 threadably mounted in the member 2 adjacent the jaw thereof, the bolt being provided adjacent one end with a flat angular portion 6, and an enlarged flat head 7. The other member 1 has a transverse slot 8 65 formed therein which is enlarged at its opposite ends as at 9, the restricted portion of the slot being substantially the same width as the thickness of the flattened portion 6 and the head 7 of the bolt, so that the 70 flattened head of the bolt may be passed through the restricted portion of the slot, whereupon the member 1 may be moved so that the flattened portion 6 of the bolt is disposed in one of the enlarged ends of the slot 75 to pivotally connect the members together. It will be understood that the member 1 may be mounted on the bolt 5 so that either 80 enlarged end of the slot therein engages the bolt, and in this manner, the distance between the jaws 4 may be adjusted. Secured to the opposite faces of each of the jaws are the guide plates 10, the inner edges of the plates projecting beyond the inner edges of the jaws, each of the plates being 85 formed intermediate of its ends, with a transverse slot 11. Each of the jaws 4 has formed in its inner edge, a transversely extending elongated recess 12 in which a dog 13 is slidably seated, each of the dogs having reduced extensions 14 which project 90 through the slots in the plates 10, whereby the dogs are guided in the jaws. Disposed between the inner faces of the dogs and the base wall of the recesses, are springs 15 95 which normally force the dogs outwardly, to dispose the outer ends of the same beyond the inner edges of the jaws. A rotary head 16 is adapted for engagement between the jaws 4 of the wrench, the projecting edges 100 of the plates 10 engaging the opposite faces of the head to maintain the same in position between the jaws. The periphery of the head is provided with a series of ratchet teeth 17 with which the spring pressed dogs 105 engage to prevent rotation of the head in one direction with relation to the jaws. To secure the jaws in any desired adjusted posi-

tion, a set screw 18 is disposed through the member 1 adjacent the slot therein, the extremity of the screw being adapted to frictionally engage the member 2, whereby the same are held in adjusted position.

The inner edge of each jaw at its inner end is provided with a pair of notches 19, the side walls of which are beveled and sharpened as at 20, so that a wire (not shown) may be placed within registering notches in the members, and upon movement of the handles toward each other, the wire will be severed by the sharpened walls of the notches. It will be seen from the drawing, that one of the notches in each of the jaws will register when the bolt 5 is disposed in either end of the slot 8, so that the wrench may be used to cut wire regardless of the adjusted position of the jaws. The inner end of the handle of the member 2 is formed into a screw driver 21, and the inner end of the handle of the member 1 is formed into a tack puller 22.

In the practical use of my improved wrench, the slot in the head 16 is engaged with a nut or other similar work (not shown) to be turned, and when the wrench is rotated in the direction of the arrow, as shown in Fig. 1 of the drawing, the head is turned with the wrench to rotate the work; but when the wrench is turned in the opposite direction, the dogs 13 ride over the ratchet teeth 17 on the periphery of the head, so that the handles of the wrench may be oscillated back and forth to turn the work home or remove the same from engagement with its support.

It will be seen, that the jaws of the wrench may be adjusted by removing the head 16 therefrom and turning the bolt 5 until the flattened portion 6 thereof is disposed in the same plane as the slot 8 in the member 1, whereupon the member may be moved so that the flattened portion 6 of the bolt passes through the restricted portion of the slot 8 to the enlarged portion of the slot at its opposite end, and in this position, the bolt may be turned so that the flattened portion 6 thereof is disposed across the end of the restricted portion of the slot. It will be seen that the springs 15 normally force the dogs 13 inwardly of the jaws, so that the reduced extensions 14 of the dogs engage the inner walls of the slots in the plates 10, the springs allowing the dogs to retract when the wrench is turned in the direction which allows the dogs to ride over the beveled faces of the ratchet teeth of the head.

In Fig. 4 of the drawing, I have illustrated an alternative form of rotatable head, in which the head 23 is formed with a tapered slot 24, to provide a "so-called" alligator wrench, the head being provided with ratchet teeth 25 on its periphery for engage-

ment with the dogs 13 carried in the jaws. In Fig. 5 I have illustrated still another alternative form of rotatable head, in which the head 26 is provided with a plurality of notches 27 in its edge, the notches being of various widths, to receive different sizes of wire, the head 26 being also provided with ratchet teeth 28 on its periphery, so that the head 26 may be rotated in the jaws of the wrench to splice a pair of wires (not shown) which may be connected in any of the notches 27.

Having thus fully described my invention, what I desire to secure and claim by Letters Patent, is:—

1. In a wrench, the combination with pivotally connected members, each of said members having a jaw at one end and a handle at its opposite end, a rotary head mounted between said jaws, and spring pressed dogs carried upon the inner edges of said jaws for engagement with the periphery of said head to prevent rotation thereof in one direction with relation to the wrench.

2. In a wrench, the combination of pivotally connected members, each of the members having a handle portion at one end and a jaw at its opposite end, plates connected to the opposite faces of said jaws, a rotatable head mounted between the jaws, said plates projecting beyond the inner edges of said jaws to engage the opposite faces of said head, the periphery of said head being formed with a series of ratchet teeth, and spring pressed dogs mounted in the inner edges of said jaws on opposite sides of said head for engagement with the ratchet teeth thereof, to prevent rotation of the head in one direction with relation to the wrench.

3. In a wrench, the combination of pivotally connected members, each of the members being formed with a handle at one end and a jaw at its opposite end, plates secured to the opposite faces of the jaws, the inner edges of said plates projecting inwardly of the inner edges of the jaws, the inner edge of each jaw having an elongated recess formed therein, each of said plates having an elongated slot formed therein which registers with the recess in its respective jaw, spring pressed dogs mounted in said recesses and having reduced extensions for engagement in the slots in said plates, a rotatable head mounted between the jaws, the projecting edges of said plates engaging the opposite faces of the head, and the periphery of said head being formed with a series of ratchet teeth to receive said dogs, whereby the head is prevented from rotating in one direction.

4. In a wrench, the combination with a pair of members each having a jaw at one end and a handle at its opposite end, one of said members having a bolt projecting therethrough adjacent its jaw, said bolt hav-

- ing a flattened portion adjacent one end thereof and a flattened head, the other member having a transverse slot formed therein adjacent its jaw, the opposite ends of said slot being enlarged, the flattened portion of said bolt being of greater width than the width of the restricted portion of the slot, whereby either enlarged end of the slot may be engaged around the flattened portion of 5 the bolt so that the members may be pivotally connected together in different adjusted positions, a rotatable head disposed between said jaws, and means for preventing rotation of said head in one direction.
- 10 5. In a wrench, the combination with pivotally connected members, each of said members having a jaw at one end and a handle at its opposite end, a rotary head having its periphery formed with a series of ratchet teeth mounted between said jaws, each of said jaws having an elongated recess formed in its inner edge, spring pressed dogs mounted in said recesses for engagement with the 15 ratchet teeth on the periphery of said head to prevent rotation thereof in one direction with relation to the wrench, and means connected to said jaws for holding said head in operative position there-between and to prevent accidental disengagement of said dogs from said jaws.
- 20 6. In a wrench, the combination with pivotally connected members, each of said members having a jaw at one end and a handle at its opposite end, a rotary head having its periphery formed with a series of ratchet teeth mounted between said jaws, the inner edge of each jaw having an elongated recess formed therein, and a spring pressed dog mounted in the recesses for engagement with the ratchet teeth on the periphery of said

head to prevent rotation thereof in one direction with relation to the wrench. 25

6. In a wrench, the combination with pivotally connected members, each of said members having a jaw at one end and a handle at its opposite end, a rotary head having its periphery formed with a series of ratchet teeth mounted between said jaws, each of said jaws having an elongated recess formed in its inner edge, spring pressed dogs mounted in said recesses for engagement with the 30 ratchet teeth on the periphery of said head to prevent rotation thereof in one direction with relation to the wrench, and means connected to said jaws for holding said head in operative position there-between and to prevent accidental disengagement of said dogs from said jaws. 35

In testimony whereof I hereunto affix my signature in the presence of two witnesses.
